LEWIS A. BOWER, OF SIGOURNEY, IOWA.

MUSIC-LEAF TURNER.

1,135,255.

Specification of Letters Patent. Patented Apr. 13, 1915.

Application filed May 10, 1913. Serial No. 766,788.

To all whom it may concern:

Be it known that I, LEWIS A. BOWER, a citizen of the United States, residing at Sigourney, in the county of Keokuk, State 5 of Iowa, have invented certain new and useful Improvements in Music-Leaf Turners; and I do hereby declare the following to be a full, clear, and exact description of the invention, such as will enable others 10 skilled in the art to which it appertains to make and use the same.

This invention relates to music-leaf turners, and it more particularly relates to an improved device of this character which is 15 particularly applicable for standard size piano-music, although it may be used for other sizes.

An object of the invention is to provide 20 an improved music-leaf turner which may be folded into comparatively small space and into convenient form for being carried from place to place.

Another object is to provide an improved 25 music-leaf turner which may be quickly operated for turning the music-leaves.

Another object is to provide an improved 30 music-leaf turner to which the sheet music may be quickly applied and operatively connected.

Another object is to provide an improved 35 music-leaf turner of this character by which the music-leaves may be quickly turned separately and by which they may be quickly returned to their initial position collectively.

Another object of the invention is to provide 40 a music-leaf turner of this character which is adapted to be set into such an intermediate position that the respective music-leaves may be quickly returned to their initial position, one by one.

Another object of the invention is to provide 45 a device of this character which is simple of construction and operation, compact, comparatively inexpensive, and thoroughly efficient.

Other objects and advantages may be recited hereinafter and in the claims.

In the accompanying drawings, which 50 supplement this specification; Figure 1 is a front elevation view of my improved music-leaf turner with a sheet of music held thereby in initial position. Fig. 2 is a somewhat similar view of the lower portion of the 55 device with a sheet of music held in the

finish or final position. Fig. 3 is a sectional view taken on the line 3-3 of Fig. 1, with certain of the turner-arms in starting position, others in finished position, and another in medial position. Fig. 4 is a view similar 60 to Fig. 3, with the turner-arms in starting position. Fig. 5 is a similar view with one of the turner-arms in finish position, and others in starting position, the turner-hook being guided over the pins of the turner-arms by 65 means of the cam surface of the bearing block. Fig. 6 is a similar view, the turner-arms being in finish position, and the turner-hook being in its initial position. Fig. 7 is a perspective view of the pusher member, 70 and Fig. 8 is a perspective view of the turner-hook.

Referring to the drawings, in which similar reference characters correspond with similar parts throughout the several views; 75 the body of this improved music supporter and turner consists of four plates or sheets of material, 10, 11, 12 and 13 respectively, hinged together at 14, 15 and 16. The plates 10 and 12 are relatively narrow, being of substantially equal width, and constituting sides of the casing which is formed by these hinged elements; while the plates 11 and 13 are substantially equal in width, and comprise the bottom and top elements 80 respectively of said casing. An end wall 17, which is equal in height to the width of the members 10 and 12, and equal in length to the width of the members 11 and 13, is secured to the bottom plate 11, and constitutes 85 the stop and support whereon the sides and top rest when the casing is closed. 90

Spaced apart from and parallel with the end wall 17 is a shelf 18, secured on the bottom plate 11; while in alinement with the shelf 18, when the casing is open, is a similar shelf 19, secured on the plate 13. These shelves 18 and 19 constitute a music-leaf support, whereon the music-leaves 20 rest, while the back or outside leaves or sheets of 100 music are engaged by leaf springs 21, pivotally secured on the plates 10 and 13 respectively, and these springs are held in normal operative position by means of springs 21', and are adapted to be turned horizontally 105 out of operative position when not in use. The casing or body is held in open position by means of buttons 22 and 23.

The music-leaves are each placed between a pair of rods or fingers 24; each pair of 110

said fingers being carried by a turner-arm 25. These turner-arms are pivoted on a common pivot 26, supported by the shelf 18 and a bearing block 27, and are adapted to swing through an angle of approximately one-hundred and seventy-five degrees, so as to turn the respective sheets of music engaged thereby. Each arm 25 is provided with a pin or stud 28, extending downwardly or in the opposite direction from the fingers 24. These studs 28 are each adapted to be engaged by a turner-hook 29, said turner-hook being apertured at 30 for the reception of the pivot 31. This turner-hook 15 is provided with a roller 32 adjacent to the notch 33, and has its end, opposite from the roller curved into U-shape, and the apertures 30 are in registry with similar apertures through a main actuating arm 34, 20 through which the pivot 31 also extends for effecting pivotal engagement of said main actuating arm and said turner-hook. This main actuating arm is mounted on a pivot 35, supported by the end wall 17 and the shelf 18, and between the pivot 35 and the pivot 31 is a pusher arm 36, pivotally connected at 37. This pusher arm is notched at 38 (see Fig. 7), and the forwardly inclined notch thereof is adapted to engage with 30 the stud 28 of the first-leaf-engaging arm 25, for the purpose hereafter specified. This pusher arm is provided with a U-shaped end portion or yoke 39 which constitutes a counter-balance, for elevating the notched end 38. The yoke is apertured at 40, and the pivot 37 extends through these apertures and through the registering apertures of the U-shaped main actuating arm 34.

The block 27 is provided with a cam surface 41, which is inclined toward the plate 12 and which constitutes a guide for directing the hook 29 into proper relation with the studs 28, for engaging the latter. A block or lug 42 extends between the bifurcations of the U-shaped arm 34, to prevent axial movement thereof on the pivot 35.

A flexible element 43 is connected to the U-shaped end of the hook 29 and connects with a retractile spring 44, which latter connects with a hook 45, the latter being secured to the plate 13. The flexible element 43 passes between pins 46 and 47, which extend through the U-shaped arm 34, and this flexible element 43 is supported at an elevation by the pin 46 during the swinging movement of the arm 34 and its adjuncts, so as to exert an outward pull on the U-shaped portion of the hook 29, thereby pressing the notched portion inward, for assuring its positive engagement with the studs 28.

Secured to one end of the pin 47, is a flexible element 48, extending laterally toward the left, through an eye 49, secured on the plate 10. A knob or knot 50 is disposed on

the end of the flexible element 48, to retain 65 its engagement with the eye 49.

In operation, assuming that a folio of music is applied, and in its initial position, as in Figs. 1 and 6, the musician, after finishing the music on the first page of a leaf, turns said leaf by pulling downward or outward on the flexible element 48, thereby causing the actuating arm 34 to swing outward and leftward, and to carry with it the turner-hook 29 and the first-leaf-engaging 75 arm, and depositing it in such position that the fingers 25 thereof rest upon the shelf 18. During this movement of the elements 34 and 29, the pin 28 of the turner-arm is engaged by the leftwardly inclined hook element which is formed by the notch 33. Now, when the flexible element 48 is released, the retractile spring 44 returns the elements 34 and 29 to their initial position, and in proper relation with the second-leaf-engaging arm; so that, when the flexible element 48 is again pulled leftward, the last said arm is also swung leftward, and this operation is repeated until all of the turner-arms have been swung leftward. Now, when it 90 is desired to return all of the music-leaves simultaneously, the flexible element 48 is pulled with greater force than is exerted in turning the leaves leftward, and this increased force causes the elements 34 and 36 95 to assume a position substantially in parallel relation with each other and with the bottom or base plate 11; so that the rightwardly inclined shoulder, formed by the notch 38, engages with the studs 28 of the first-leaf-engaging turner-arm, and when the flexible element 48 is again released, the spring 44 draws the elements 34, 36 and 35 rightward, during their operation, the stud 28 of each turner-arm is engaged by the contiguous turner-arm, so that all of the arms 25 are returned simultaneously, and if allowed to return with sufficient momentum, they will immediately return to their initial position. However, if it is desired to return 110 only one, two or more (and not all) of the leaves, the flexible element 48 is released gradually, so that the pin 28 of the initial turning-arm is engaged by the detent 33, so that the turner-arms are now supported at 115 an angle of approximately forty-five degrees from the base plate 11, and the turner-arms which are engaged with the last few pages of the music are free to be turned by hand into their initial position.

It will be seen that I have provided a music turner of this character which is fully capable of attaining the foregoing objects in a thoroughly practical and efficient manner.

I do not limit my invention to the exact details of construction, combinations and arrangements of parts, as herewith illustrated

and described, but my invention may only be limited by a reasonable interpretation of the claim.

I claim:—

- 5 In a music leaf turner, a body, shelves secured thereto and adapted to support a folio of music, a plurality of arms pivotally secured on said body, fingers on the ends of said arms arranged to be secured to the
- 10 leaves of the folio, an actuating arm pivotally secured to the body, a turner hook pivotally secured to said actuating arm, a return arm pivotally secured to said actuating arm and having one end thereof contacting
- 15 with the body, an actuating element secured

to said actuating arm, the turner hook being constructed and arranged to successively engage the aforementioned pivotally supported arms, and move the same in one direction, the turner hook being adapted to engage one 20 of the said last mentioned arms and to turn all of the said arms simultaneously to their initial positions, and resilient means for actuating said turner hook.

In testimony whereof I affix my signature 25 in the presence of two witnesses.

LEWIS A. BOWER.
